SNOWPLOW

Filed May 25, 1925

Inventor:
Emery H. Fahrney
By R. Lehman
Atty.

UNITED STATES PATENT OFFICE.

EMERY H. FAHRENEY, OF CHICAGO, ILLINOIS.

SNOWPLOW.

Application filed May 25, 1925. Serial No. 32,583.

This invention relates in general to snow plows of the type in which there is employed a rotary impeller for delivering the snow from the machine, but more specifically the 5 invention relates to improved means adapted for use in connection with the impeller whereby the snow or matter handled by the impeller will be deflected to one side of the impeller and which means also serves to 10 prevent the material from piling up and obstructing the delivery of the material from the chute of the impeller.

A further object is to provide an improved device of this character which may 15 be readily detached from and as readily applied to the machine.

To the attainment of these ends and the accomplishment of other new and useful objects as will appear, the invention consists in 20 the features of novelty in substantially the construction, combination and arrangement of the several parts hereinafter more fully described and claimed and shown in the accompanying drawing illustrating this invention, and in which

Figure 1 is a front plan view of the scoop of a snow plow and impeller with a casing for the impeller, and chute having an attachment applied thereto constructed in accordance with the principles of this invention.

Figure 2 is a detail top plan view of the attachment.

Referring more particularly to the drawing the numeral 10 designates generally a scoop having an opening 11 in the bottom thereof, beneath which opening is arranged an impeller 12 of any suitable construction. The impeller casing is provided with a delivery or discharge chute 13 open at its end as at 14. All of the above referred to parts may be of any desired and suitable construction.

Supported in any suitable manner adjacent the outlet of the chute 13 is a frame of any suitable construction and designated generally by the reference numeral 15. This frame is detachably secured in position in any suitable manner preferably by means of 50 fastening bolts or devices 16, which latter are connected with suitable brackets 17. These brackets may be of any suitable construction and may be secured in any suitable manner to the rotor casing, preferably to the 55 exterior of the delivery chute 13.

The frame 15 preferably projects beyond

the extremity of the outlet of the chute 13 and plates or members 18 may be supported by the frame, the frame members being tied or fastened together by means of a suitable connecting member or plate 19. Supported by the frame thus formed and in advance of the extremity of the chute are suitable brackets 20-21 which respectively form bearings for shafts 22-23 and to which shafts are respectively connected sprocket wheels 24-25.

Supported also by the frame and at any desired point in the rear of the brackets 20 and 21 are additional brackets 26 in which 70 a shaft 27 is journaled, and to which shaft sprocket wheels 28 are connected.

Endless chains 29 pass over the respective sprocket wheels, and connected with these chains and extending across the space therebetween are elements 30, and which elements are adapted to be successively moved during the travel of the chains 29 so as to extend across but in advance of the outlet 14 of the chute 13, so that material directed through the chute 13 by the impeller 12 will contact with the elements 30 which are in alinement with the end of the chute to deflect the material laterally with respect to the chute. The endless element thus constructed is adapted to be given a constant direction of rotation in any suitable manner and is constantly rotating during the operation of the machine so as not only to deflect the material discharged from the chute but also operates as 80 a means for preventing the material from clogging at the outlet of the chute.

A simple and efficient means for imparting motion to the endless element embodies 90 a pulley wheel 31 which is connected with the shaft 27 for rotation therewith, and motion may be imparted to the pulley wheel 31 in any suitable manner but preferably from some suitable moving part of the mechanism.

Guides 32 are preferably supported by the frame 15 to support and guide the elements 30 as they pass across the end of the chute and these guides 32 preferably arch from one side of the chute to the other, as shown in Figure 1.

When desired the endless element and the supporting frame 15 may be readily removed by detaching the fastening bolts or devices 16.

While the preferred form of the invention has been herein shown and described it is to

be understood that various changes may be made in the details of construction and in the combination and arrangement of the several parts, within the scope of the claims, without departing from the spirit of this invention.

What is claimed as new is:—

1. In combination, an impeller, a casing therefor having a discharge outlet, and a traveling abutment operating independently of the impeller and disposed adjacent the said outlet and extending in a direction across the outlet for directing the course of travel of the material delivered through said outlet.
2. In combination, an impeller, a casing therefor having a discharge outlet, a movable abutment independent of the impeller and disposed adjacent and extending across the said outlet for deflecting the material delivered through said outlet, and means for imparting movement to the said abutment with respect to the said casing.
3. In combination, an impeller, a casing therefor having a discharge outlet, a movable abutment independent of the impeller and disposed adjacent and extending across the said outlet for deflecting the material delivered through said outlet, means for imparting movement to the said abutment with respect to the said casing, and means detachably securing said abutment in position.
4. In combination a discharge chute, an impeller spaced from the outlet end thereof, an abutment disposed adjacent the outlet of the chute and against which the material strikes after it leaves the impeller, said abutment operating to deflect the material delivered through the chute, and means for imparting motion to the abutment to cause the same to travel across the outlet of the chute.
5. In combination, a chute having a discharge outlet, an impeller spaced from the outlet, a traveling abutment spaced from the impeller and arranged adjacent the outlet and extending thereacross and against which the material strikes after leaving the impeller, said abutment operating to deflect the material delivered through the outlet, and means for moving the abutment in a constant direction and transversely of the said outlet.
6. In combination, a chute having a discharge outlet, a traveling abutment arranged adjacent the outlet and extending there-

across for deflecting the material delivered through the outlet, means for moving the abutment in a constant direction and transversely of the said outlet, and means removably securing the said abutment in position.

7. In combination, a chute having a discharge outlet, an endless traveling abutment adjacent the chute, one run of the abutment extending transversely of the said outlet for deflecting the material delivered through the chute, means for imparting motion to the abutment, and means detachably secured to the chute for supporting the said abutment.

8. In combination, a chute having a discharge outlet, an endless traveling element supported adjacent the said outlet, one run of the said element traveling across and spaced from the end of the said outlet for deflecting the material delivered through said outlet, and means for imparting movement to the said endless element.

9. In combination, a chute having a discharge outlet, an endless traveling element supported adjacent the said outlet, one run of the said element traveling across and spaced from the end of the said outlet for deflecting the material delivered through said outlet, means for imparting movement to the said endless element, and means extending for a considerable distance along the path of movement of the said run of the said endless element for supporting and guiding the same.

10. In combination, a chute having a discharge outlet, an endless traveling element supported adjacent the said outlet, one run of the said element arching across the said outlet from one side thereof and operating to laterally deflect the material delivered through the said outlet and thereagainst, and means for imparting a traveling movement to the said endless element.

11. In combination, a chute having a discharge outlet, an endless traveling element supported adjacent the said outlet, one run of the said element arching across the said outlet from one side thereof and operating to laterally deflect the material delivered through the said outlet and thereagainst, and means for imparting a traveling movement to the said endless element.

In testimony whereof, I have signed my name to this specification, on this 11th day of May, 1925.

EMERY H. FAIRNEY.
